DRIVING AND PULLING OF PILES, PILE PLANKS, TUBING, AND THE LIKE

Francois Berthet, Algiers, Algeria, and Jacques Desvaux, Paris, France

Application October 31, 1950, Serial No. 193,202

Claims priority, application France November 4, 1949

8 Claims. (Cl. 61—73)

In driving piles, pileplanks, as well as tubing or casings of the type used for moulding piles in the ground, pile-drivers are generally used, in which the ram acts directly on the end of the pile, etc., opposite from that which is to penetrate the ground.

This method requires very large-size driving apparatus, often very expensive and taking up a large amount of power. Moreover, because the rigidity of piles or pileplanks to buckling stresses is limited, the method can only be applied where the ratio of the height to the cross-section of the piles or pileplanks does not exceed a definite limit. In the case of concrete piles, it necessitates the use of grades of concrete possessing a very high crushing strength. All these limitations seriously burden the cost of piling and similar structure.

In addition to these drawbacks, the usual pile-driving process generates vibrations in the area surrounding the driving site owing to the high impacts involved. These vibrations may prove a hazard to adjacent structures if any, so that in such cases the said method of pile-driving cannot be used.

In heterogeneous soil, vertical driving is at times made very difficult because of the obstacles met with or because of the characteristics and nature of the terrain. Often there is a tendency for the pile to deviate and bend, developing strains which are liable to impair its strength or its subsequent firmness.

These difficulties may in part be averted by the use of another driving technique more particularly applicable to tubing and which consists of imparting to the length of tubing being driven a reciprocating rotary motion by means of levers or a jib connected to collars clamped about tube. Such motion, cooperating with the gravity of the tubing will sometimes result in a gradual sinking of the tube without violent and repeated impacts. However this method still requires, in its usual embodiments, a powerful and cumbersome equipment, as well as a great expenditure of power. Its use remains very costly. Besides, it does not quite eliminate the possibility of deviation.

For pulling piles, pipeplanks, tubing and the like, the means used are generally similar to those employed in driving them. Thus, a pile-driver may be used with an inverted action of the ram, in combination with jacks, winches and tackle. Alternatively a reciprocatory rotary motion may be applied, cooperating with the effect of vertical upward pull exceeding the gravity of the pile or tubing plus the surface friction forces.

In either case, the same limitations as in driving are come up against, namely the requirement of a powerful and cumbersome equipment.

To facilitate pulling and even contingently driving operations, it has already been suggested to loosen the pile or tubing by applying lateral impacts to it or further by imparting to it a continuous vibration. Such means make it possible to reduce the pulling stress. They have the further advantage of increasing the regularity of the vertical displacement of the pile or tubing, and especially

2

that of preventing, in the case of a tube, the accidental ingress of earth into the space cleared as it is pulled out. But these are no more than accessory and contingent expedients which do not replace the essential operating units, the use of which still remains necessary with their attendant above-mentioned drawbacks.

It is the object of this invention to obviate these shortcomings and to achieve fast, efficient, flexible and regular driving and pulling operations.

10 The invention consists of associating with the pile, pile-plank, tube or the like—hereinafter generally designated by the term "pile"—a device adapted to impart to it alternating impulses which are oriented in predetermined constant directions and, basically, balanced. These impulses may be oriented either axially of the pile, or normally thereto, or both axially and normally to the pile. They are balanced in that they are imparted to the pile directly in the direction of its axis, or to both sides thereof in one or more diametric planes.

20 The impulses oriented along the axis are made to act alternately toward the foot and toward the head of the pile. In one direction they combine additively with the weight of the pile while in the other they detract therefrom, thus creating alternating variations in the thrust against the bottom of the driving hole.

25 The impulses when oriented in a direction normal to the axis generate an alternating torque which imparts to the pile alternating movements of rotation. These movements may be varied in amplitude according to operating conditions.

30 The device associated with the pile may also be so designed as to impart simultaneously to it alternating impulses both along its axis and perpendicularly to its axis. The alternating motion due to the transverse impulses cooperates with the alternating forces exerted along the axis to produce the desired pile-driving or -pulling action.

35 Owing to these means, the driving and pulling of piles may be performed with a reduced equipment, very readily transportable and easy to install, small in size and requiring a reduced energy output to operate. Pile-driving and -pulling operations may thus be very economically accomplished.

40 The application of oriented alternating impulses according to the invention results in an increased rate of feed of the driven pile, and in a very quick and progressive rate of extraction, particularly valuable advantages in the case of large-sized pile elements or in heterogeneous or hard ground. The vibrating device and pile assembly, remain at all times in a balanced condition, and 45 verticality is thereby promoted in the more usual case where vertical piles are involved, moreover this suppresses harmful lateral stresses, responsible for inclined piles and ovalized tubing, all defects very difficult to correct. Moreover, the pile-driving operation is performed without necessitating the use of anchoring or similar means for supporting the device of the invention upon the ground.

45 The amplitude and frequency of the oriented impulses are predetermined as a function of the shape and mass of the pile. They are adjustable by varying the position, 50 and contingently the inclination and/or other characteristics of the oscillatory elements used.

55 The invention will now be described in greater detail with reference to the accompanying drawings which relate more specifically but not exclusively to the driving of vertical piles and wherein:

60 Figures 1 and 2 diagrammatically illustrate the arrangement of a pile having mounted on it a device for generating vertical vibratory impulses;

65 Figure 3 is a diagrammatic view in perspective showing how horizontal impulses may be produced;

70 Figure 4 is a diagrammatic view showing how both

vertical and horizontal impulses may be imparted to the pile concurrently;

Figure 5 is a diagrammatic view of a different and simplified embodiment;

Figure 6 illustrates in elevation the device of Figure 5 as adapted to a large-diameter tubing or pipe section;

Figure 7 is a view partly in horizontal section, partly in plan on line VII—VII, of the device of Figure 6;

Figures 8 and 9 illustrate on a scale different from that of Figures 6 and 7 the application of the invention to a prefabricated pile of usual type; Figure 8 is partly an elevation and partly a section while Figure 9 is a cross-section on line IX—IX of Figure 8;

Figure 10 is a modification of the arrangement of Figure 8;

Figure 11 relates to the driving of tubing from on board ship; and

Figure 12 is a perspective view of a modified embodiment.

As shown, a pile 1 is to be driven into the ground. To drive the pile 1, according to the invention, the effect of oriented vertical oscillatory impulses is combined with the action of its weight.

For this purpose, there is integrally connected with the pile 1, e. g. on the top thereof, a frame 2 having its axis of symmetry extending along a diameter of the pile, and carrying vibrator units variable in frequency. These units may for instance consist of a pair of heavy vertical discs 3 and 4 arranged in a common vertical plane of the pile 1, and symmetrically placed with respect to it and rotated in opposite directions, as indicated by the arrows A. The disc 3 carries an eccentric unbalancing weight 5 and the disc 4 an unbalancing weight 6. The unbalancing weights 5 and 6 are maintained at all times symmetrical and in phase with respect to each other. The motion of the discs 3 and 4 is synchronized.

The discs or fly-wheels 3 and 4, owing to their in-phase unbalancing means 5 and 6, create forces which possess vertical components f alternating and variable in magnitude. The horizontal components are opposite from each other and cancel each other out at all times. The vertical components f are transmitted to the frame 2 and the pile 1 and impart thereto an alternating vertical force in the direction of the arrows F₁-F₂. When the impulse is exerted in the downward direction F₁ it adds to the weight of the pile 1; when in the upward direction F₂ it detracts therefrom; thus the compressive thrust on the ground at the bottom end of the pile 1 is subjected to cyclic variations which provide repeated shocks which, added to the weight of the pile 1, promote its sinking movement. The same action also facilitates extraction.

Instead of arranging the unbalanced discs at the end of the pile 1, they may be placed substantially on the axis thereof. In Figure 2, the pile 1 is shown provided with a frame 2 carrying a horizontal shaft 7 on the central portion of which three unbalanced discs or fly wheels 8, 9 and 10 are rotatably mounted and driven by suitable means. The centre disc 9 carries an unbalancing weight which is double the weight of each of the unbalancing weights of the side discs 8 and 10. The central disc 9 revolves in reverse from and at the same speed as both side discs 8 and 10. The rotations of the disc 9 on the one and the discs 8 and 10 on the other are so synchronized that the unbalancing weights thereof will always be in phase, the weights of 8 and 10 both simultaneously reaching either their uppermost or lowermost position as the double weight of the disc 9 reaches its corresponding position.

It will be seen that with this arrangement, while the horizontal components due to the action of the eccentric weights at all times cancel one another out, their vertical components combine, resulting in alternate stresses F₁, F₂ as in the case of Figure 1, which add to or detract from the weight of the pile.

The frequency and amplitude of the vertical impulses

imparted to the pile 1 are selected in correlation with the nature and shape of the pile and with the character of the ground into which the pile is to be driven. The frequency is easily varied by acting on the speed of rotation of the discs (3 and 4 or 8, 9, 10). The amplitude is adjusted by the magnitude of the unbalancing weights of the discs as well as by their degree of eccentricity.

In order to impart to the pile horizontally-oriented alternating impulses, the pile is provided with a frame 2 carrying horizontal discs 11 and 12 (Fig. 3). The discs are placed with their axes of rotation vertical and parallel to the axis of the pile 1, and symmetrically relatively to said axis. They are rotated in a common direction as indicated by the arrows B. The disc 11 carries an unbalancing weight 13 and the disc 12 an unbalancing weight 14; the unbalancing weights 13 and 14 are displaced 180° from each other. The rotations of both discs, driven by conventional means, are synchronized.

The discs 11 and 12, owing to their displaced unbalancing weights, develop forces which possess equal and opposite horizontal components g perpendicular to the frame. These forces g create a couple variable in magnitude and in direction which, transmitted to the pile 1, imparts to it alternating oscillations in the direction of rotation in the directions G₁, G₂. These alternating impulses facilitate penetration into the ground in a manner similar to the alternating movements of the known method mentioned hereabove, but have a higher rate of frequency. They are produced in a continuous manner during the rotation of the discs without special operations.

The frequency of the horizontal impulses may be adjusted by varying the speed of rotation of the discs 11 and 12. Their amplitude is determined by the spacing of the discs from the axis of the pile, and by the mass and eccentricity of the unbalancing weights 13 and 14. The magnitude of the alternating rotations G₁, G₂ can thus be varied within a wide range, in response to varying operating conditions. While this rotation may desirably assume a substantially high value in the case of a circular pile, it is evident that with a pile of hexagonal cross-section, pileplanks or the like, the amplitude of the rotation should remain limited. The versatility of the device shown will conveniently and flexibly respond to such varying conditions.

In certain stages of the pile-driving or -pulling work, it may be desirable to achieve a condition in which the horizontal alternating forces of rotation do not act symmetrically with respect to the axis of the pile, for instance to promote the separation of the walls of the pile from the surrounding ground or to facilitate penetration or force aside any particular obstacle that may occur. This may very easily be done according to the invention by acting on the spacing of either one of the discs or on the mass or eccentricity of one of the unbalancing weights without altering the position or mass of the other disc or weight.

In order to obtain the benefit both of the vertical alternating forces and the motion of alternating rotation, vertical impulses may be combined with horizontal ones in the manner shown in Figure 4.

The frame 2 mounted on the pile 1 is adapted to receive simultaneously a pair of vertical unbalanced discs or fly-wheels 3 and 4 arranged in a common diametric plane, similar to those shown in Figure 1, and a pair of horizontal unbalanced discs 11 and 12 similar to those of Figure 3. The discs 3 and 4 revolve at a common speed and in opposite directions (arrows A). Their unbalancing weights 5 and 6 are so set as to be in phase. The discs 11 and 12 revolve in a common direction (arrows B) and their unbalancing weights 13 and 14 are 180° out of phase.

With this arrangement, there are simultaneously produced according to the previously-described mechanism, vertical alternating forces F₁, F₂ and alternating rotational actions or couples G₁, G₂. These rotations co-oper-

ate with the vertical forces in promoting the driving, or pulling, of the pile 1.

The vertical impulses may be adjusted in amplitude and in frequency independently from the horizontal impulses. Such adjustments are predetermined separately in correlation with the conditions of operation.

Rather than two separate balanced pairs of unbalanced discs such as 3-4 and 11-12, a single pair of associated and synchronized unbalanced discs may be used to produce the combined horizontal and vertical impulses, as illustrated in Figure 5.

Arranged on a support 2 mounted on the end of the pile 1 are two discs 15 and 16 rotatable on horizontal axes, the axes of both discs lying on a common diametric plane of the pile 1 and in alignment with one another. The discs are provided with unbalancing weights 17 and 18. They revolve at the same speed, the disc 15 in the direction of the arrow C, and the disc 16 in that of the arrow D. The unbalancing weights 17 and 18 are disposed in-phase with each other, that is to say they reach their uppermost and lowermost vertical positions simultaneously.

At each revolution, the assembly comprising the discs 15 and 16, the frame 2 and pile 1 is subjected to a two-fold alternating impulse both in the vertical direction, which imparts to the discs an oscillatory motion in a vertical direction (arrow F) and in an angular direction (arrow G), the effect of which is similar to that previously obtained and explained in connection with Figure 4.

Adjustment of the horizontal torque imparting the alternating rotation G is effected, independently of any action on the vertical forces F, by acting on the spacing of the discs 15 and 16 or of the unbalancing weights on these discs, from a plane normal to their common axis. The vertical impulses may alternatively be adjusted by varying the mass and eccentricity of the weights 17 and 18. The frequency of the impulses is of course determined by the speed of rotation of the discs 15 and 16.

In the foregoing description it has been assumed, for the sake of simplicity, that the device associated with the pile 1 only comprises a single pair of discs placed on a common diametric plane (Figs. 1, 2, 3 and 5) or two pairs of discs one pair horizontal and the other vertical, disposed on a common diametric plane (Fig. 4). It should be understood however that the number of pairs of discs associated two by two on a common diametric plane, may have any suitable value. In some cases, successful results may be attained by spacing the discs in a plurality of radial semi-planes, spaced by equal angular intervals apart. All such discs carry unbalancing weights set in-phase with one another. They are rotated in a common direction as seen by an observer lying along the centre axis of the pile and looking at the disc under consideration. The large number of associated discs or pairs of discs makes it possible to distribute the effects throughout the entire cross-section of the pile and thus to reduce the size of the individual discs or pairs of discs and the mass of the unbalancing weights required for the accomplishment of a given result.

According to an alternative construction, the unbalancing weights set in in-phase relationship on a plurality of discs may be replaced by a continuous annulus moved horizontally and vertically in an appropriate alternating motion. This annulus may be hollow and weighted in a variable manner depending on the forces to be developed.

Figures 6 and 7 illustrate a form of embodiment of the arrangement shown in Fig. 5, as applied to a tubing element for drilling a shaft which is to serve e.g. to cast concrete in order to make a foundation pile.

The tubing or casing 20 provided with a penetrating element or bit 21 is herein illustrated as in the process of being driven, having already penetrated to a substantial depth into the ground. Secured to its top is a platform 22 carrying the unbalanced fly-wheels or discs 23 and 24 which are to impart both vertical and horizontal impulses

to the tubing. The platform 22 is mounted over the top of tubing 20, thus eliminating the necessity of providing any securing means such as collars or jacks. The platform is rigidly connected with the tube 20 by any suitable means, such as keying means or bolts for example. It is statically balanced, such balancing being where necessary rendered more perfect by the use of a counterweight 25. The unbalancing weight of the fly-wheel 23 is shown at 26; the fly-wheel 24 is provided with an identical unbalancing weight 27 arranged to remain in phase with the weight 26.

The fly-wheels 23 and 24 are driven in rotation respectively by the electric motors 28 and 29 through an appropriate transmission, e. g. a worm 30 and worm-gear 31. The motors are arranged to impart reverse rotations to the fly-wheels 23 and 24; the rates of rotation of the fly-wheels are synchronized, for instance, by means of a mechanical transmission 32 including a bevel-gearing 33. The rotations may be synchronized in any other way, as for instance by an appropriate electrical drive for both motors 28 and 29.

During the tube-driving operation, the motors 28 and 29 drive the fly-wheels 23 and 24 in rotation, and these impart to the platform 22, in the manner previously described, an oscillatory motion which comprises both vertical and horizontal components, so that the tube 20 is made to sink.

To guide the tube over the first few yards of its descent, it may be desirable to provide a guide tube 34 preliminarily arranged in the ground at the selected site. This tube 34 will assure verticality in the initial phase of the driving process. Thereafter the casing 20 will sink in smoothly without being subjected to any lateral stresses. In heterogeneous or broken ground any obstacles encountered are attacked very gradually and with great power, the pressures set up per square inch of attacking area being very high. The initial guiding will therefore, as a rule, be sufficient to keep the tube vertical. If not, resort would be had to the provisions for displacing one fly-wheel or one unbalancing weight relatively to the other wheel or weight, for the amount of time required in order to restore verticality.

After one length of the tubing 20 has been fully driven, the platform 22 is removed and mounted on the next length of tubing, which is connected with the first length by a suitable coupling mechanical or otherwise.

It will be noted that, in the arrangement shown, the interior of the tubing remains at all times accessible for earth removal. If the drilling is made through hard rock, a platform similar to 22 may be mounted on a chisel-drill guided within the tubing in order to break up the rock and facilitate its removal from out of the tubing.

By suitably selecting the rate of rotation, the mass and eccentricity of the unbalancing weights 26 and 27 and the mass of the fly-wheels or discs 23 and 24, relatively to the mass of the tubing, vertical impulses of adequate magnitude are obtained for driving the tubing. Associated with these impulses is a horizontal alternating torque adjustable in value by acting on the spacing of the fly-wheels 23 and 24 and/or of the unbalancing weights 26 and 27.

In order to adapt the oscillatory impulses to the weight of the pile to be driven or pulled, to the various stages of the driving or pulling operation, to the firmness of the ground and to the lateral friction stresses, the motors 28 and 29 are desirably variable-speed units allowing the speed of rotation to be gradually varied as the driving or pulling operation proceeds.

The lateral friction of the ground is comparatively low owing to the absence of any lateral strains. Torsion of the tubing 20 remains low, negligible even in the case of thick tube sections, so that the impulses are transmitted through to the bottom end of the tubing, down to the penetrating bit. In practice, the speed of the fly-wheels, for a given unbalancing weight, is limited to a value con-

sistent with the strength of the ball or roller bearings used. On the other hand this speed cannot be reduced to a value less than a certain limit below which the dimensions of the components would be so large as to be out of proportion with the practical conditions of operation on a work-yard.

It may be stated by way of indication that, with a tubing 2 meters in diameter, fly-wheels 2 meters in diameter provided with unbalancing weights 120 kilograms each, spaced from each other by 4 meters and rotated at 7 revolutions per second maximum speed at the end of the driving operation, there is developed a horizontal couple of about 100 tons-meters, a vertical force of about 100 tons and a satisfactory amplitude of rotational reciprocation. The weight of the fully equipped platform remains less than 3 tons for a 50 ton tube section. The direct current-supplied drive motors are 45 H. P. in capacity and are controlled from a 120 H. P. Ward-Leonard set which enables the speed of rotation to be continuously varied with the thrust required during the drilling process. At a speed of 10 rev. per sec., a 200 ton-meter torque is available, and a vertical force of about 200 tons.

There are not many usual types of ground extant capable of opposing a resistance to drilling which cannot be overcome by equipment having the above-defined characteristics.

Figures 8 and 9 illustrate one embodiment of the apparatus of the invention, of the general type diagrammatically shown in Figure 5, as applied herein to a pre-fabricated pile.

Mounted on the pile 35 at a convenient vertical position thereon, is a platform 36 carrying the vibrator units. The platform 36 is secured to the pile by clamping collars 37, 38. Preferably the platform 36 is provided with keying means 39 adapted to fit into suitable sockets or recesses 40 formed at casting in the pile 35.

The platform 36 carries two fly-wheels or discs 41 and 42 provided with unbalancing weights 43 and 44 driven at a common speed by two electric motors 45 and 46 synchronized electrically with each other. The motors are herein shown as arranged with their shafts vertical. Each motor drives the related fly-wheel by a transmission including a worm and worm-gear 47-48. This arrangement has an advantage over that shown in Figs. 6 and 7 in that it avoids the exertion of longitudinal stresses by the rotors of the motors upon the end bearings. It is of course applicable to the case of a tubing or to any other case as well.

The operation of the fly-wheels generates vertical alternating forces which combine additively with the weight of the pile 35 and cause the pile to sink smoothly in. This downward movement of the pile is facilitated by the horizontal alternating torque. During the first few feet of the driving operation, it is desirable to provide a guiding structure or simply a ring 49 of added or compacted earth or grout, which will hold the pile vertical in the initial phase of the driving. After the pile has bored through the ring 49, it will continue to sink in smoothly, retaining its direction. As the platform 36 reaches a point near the ground level, it is removed and again secured at a suitable vertical height on the pile 35, which may have been formed, e. g. at casting, with the suitable sockets 40 at suitably spaced points therealong.

It may be stated by way of indication that, with a pile 0.400 meter in diameter and 15 meters long, fly-wheels are used which are 1 meter in diameter and carry 50 kilograms unbalancing weights. These fly-wheels are driven at a variable speed which may reach as much as 10 revolutions per second towards the end of the driving operation. Piles may thus be driven smoothly and efficiently into the majority of usual grounds.

Figure 10 illustrates a similar arrangement for driving a pile, but herein the fly-wheels are driven by a single motor. Secured to the top of pile 50 by an interfitting

coupling 52 or any other suitable means is a frame 51. The platform carries a pair of vertical unbalanced fly-discs 53 and 54. The fly-discs are driven by a common motor 55 mounted on the frame 51 in a vertically centred position relatively to the pile, in the axial area thereof.

This single-motor arrangement can also be used with a tube 35 such as that shown in Figures 6 and 7. Such an application is shown in Fig. 11. It is to be observed that in this case the solid platform 51 will prevent the removal of earth from within the tube 35 during the driving operation. This earth can then be cleared at the same time the platform 51 is removed to connect the next length of tubing to the length already in place.

The invention is applicable to the making and positioning of conventional foundation piles, pre-fabricated piles or piles molded in the ground, sheetpiling, etc. whether in level or sloping terrain. It is applicable in muddy ground and for work under water, in particular in the ocean. No ground anchoring support is required in connection with the apparatus of the invention.

Figure 11 shows how a tubing 35 may be driven from a boat or pontoon 56. The length of tubing 35 fitted with its platform 51 provided with the vibrator units, is directed by a guiding structure 57 formed on the boat 56. The tube sinks easily into the bottom under the combined effect of its weight and of the pulses imparted to it by the fly-wheels or discs 53-54.

It is further possible to prevent the occurrence of such shocks by arranging the motors on a platform separate from the pile to be driven. In such case, the unbalanced discs are driven through a suitable flexing coupling transmission, such as a sliding cardan joint system.

It will be noted that with the arrangement of Figures 5 to 11, the variations in the pressure of the pile on the ground and the variations in the horizontal torque, are not in phase. The thrust against the ground is not the same for either direction of the horizontal movement. The rotation of the pile is greater when the unbalancing weights are on their upward stroke than when their effect is applied downwards against the bottom. At each cycle therefore, the pile will revolve by an amount equivalent to the differential between both corresponding angular displacements. This results in a continuous circular rotation. This movement may if desired be reversed by reversing the rotation of the motor or motors.

It will be understood that all of the transmissions involved in the operation of the apparatus may be effected by means of cardan couplings, "flectors" or other flexible connections; also, the motors and/or bearings may be flexibly mounted on the platform to prevent the transmission of impacts thereto.

Figure 12 illustrates a modified form of embodiment of the method of the invention. Secured to the tubing 50 is a platform 51 carrying two unbalanced fly-wheels or discs 53 and 54. Resiliently connected with the platform 51 through springs 58 slidably surrounding the rods 59 is a frame 60 carrying a single electric motor 61. This motor can be supported through the rod 62 from a tackle or pulley-block 63 which may be adjusted in height by winding and unwinding the cable 64. The upper pulley of the tackle or pulley-block 63 is fastened at 65 to a beam or other suitable fixed support 66. The fly-wheels are driven from the motor 61 through a slideable coupling 67 and an angle gear or the like housed within the carter of the platform 51.

The flywheels have holes 68 for adjusting the unbalanced weight.

By winding or unwinding more or less the cable 64 and thus adjusting the relative spacing between the two pulleys of the pulley-block, the motor 61 is allowed to move down or up to follow the sinking or rising movement of the tubing 50 to protect the motor 61 from the vertical vibrations or impacts applied to the tubing 50.

All of the arrangements described may be used both

for driving and for pulling. In the latter case, the impulses should be increased in frequency and reduced in amplitude, for all that is then required is to cause the sides of the pile to separate from the surrounding ground. Lighter weight fly-wheels revolving at higher speeds should then be used.

All of the embodiments described and illustrated were given by way of illustration rather than limitation, and the invention should be understood as being applicable to piles and the like of all description and shape and capable of being practised in many modified ways. In the claims, the term "pile" is to be understood as having the generic meaning defined in the preamble to this specification.

What we claim is:

1. Apparatus for actuating piles, tubing, sheetpiling and like elements, comprising at least one source of alternating impulses adapted to be permanently bodily connected with said element throughout the actuation thereof, said source being balanced with respect to the axis of said element and adapted to generate simultaneously both linear alternating impulses directed axially of said element and rotary alternating impulses in a plane normal to said axis, a pair of similar axially aligned rotatable members, means for securing the members to the element with the members mounted for rotation about an axis extending diametrically of the element and perpendicular to the axis of the element with the members spaced at substantially the same distance from the axis of the element on opposite sides thereof, the center of gravity of each member being eccentric to the axis of rotation thereof, and means for rotating the members about their axis in unison in opposite directions with the centers of gravity of the pair of members in phase with each other.

2. Apparatus for actuating piles, tubing, sheetpiling and like elements, comprising a plurality of sources of alternating impulses adapted to be permanently rigidly secured to said element throughout the actuation thereof, said sources being spaced and balanced with respect to the axis of the element and adapted to generate simultaneously both alternating linear impulses directed axially of the element and alternating rotary impulses about the axis of said element each source comprising a pair of similar axially aligned rotatable members, means for securing the members to the element with the members mounted for rotation about an axis extending diametrically of the element and perpendicular to the axis of the element with the members spaced at substantially the same distance from the axis of the element on opposite sides thereof, the center of gravity of each member being eccentric to the axis of rotation thereof, and means for rotating the members about their axis in unison in opposite directions with the centers of gravity of the pair of members in phase with each other.

3. Apparatus for actuating piles or the like comprising a support rigid with the pile, a coaxial pair of vertical, eccentrically weighted fly-wheels on said support symmetrically disposed relative to the axis of the pile, said fly-wheels being mounted for sliding movement along a common axis thereof for adjustment of the spacing of said fly-wheels from the axis of said pile, means for driving said fly-wheels in rotation, the eccentric weighting means of said fly-wheels being arranged to remain continually in phase so as to reach their uppermost positions together and their lowermost positions together at each revolution, the rotation of said fly-wheels imparting to said pile simultaneously both vertical and horizontal balanced impulses adjustable by variation of the speed of rotation and of the weighting of said fly-wheels and adjustment of the spacing of the fly-wheels along their common axis.

4. Apparatus for actuating piles or the like comprising, for use in combination with a pile, a platform adapted to be secured to said pile to form an integral unit there-

with, a pair of coaxial axially spaced vertical fly-wheels on said platform and parallel eccentric weighting means on said fly-wheels disposed symmetrically with respect to the axis of the pile, two motor means rotating said fly-wheels, means for synchronizing the speeds of said fly-wheels, the weighting means of said fly-wheels being arranged to remain continually in phase, so that the weighting means of both wheels will simultaneously reach their uppermost positions and will simultaneously reach their lowermost positions, rotation of said wheels imparting to said pile simultaneously both vertical and horizontal balanced impulses adjustable by variation of the speed of rotation adjustment of the weight of the weighting means and adjustment of the spacing of the fly-wheels along their axis.

5. Apparatus for actuating piles or the like comprising, for use in conjunction with a pile, a platform adapted to be unitarily secured to the pile, a pair of coaxial axially spaced vertical fly-wheels on said platform, motor means rotating both fly-wheels, and parallel eccentric weighting means on said fly-wheels symmetrically disposed with respect to the pile axis and arranged to remain continually in phase so as to pass together through their uppermost position and together through their lowermost positions, rotation of said fly-wheels imparting to the pile balanced impulses both vertically and horizontally, said impulses being adjustable by variations of the speed of rotation, weight adjustment of the weighting means and adjustment of the spacing of the fly-wheels along their common axis.

6. Apparatus for actuating piles or the like comprising, in combination with a pile, a platform secured to the pile, a pair of axially aligned fly-wheels disposed in spaced parallel vertical planes and rotatably mounted on a horizontal axis lying in a plane common to a diameter of the pile, means mounting said fly-wheels on said platform and eccentric weighting means on each wheel, said means disposing said wheels with the wheels symmetrically disposed in relation to the axis of the pile, a motor on said platform, a sliding connecting means between said motor and said wheels adapted to drive said wheels in rotation in unison in opposite directions in planes substantially normal to the axis of the pile with said unbalancing means in phase with each other.

7. Apparatus for actuating piles or the like which comprises, for use in combination with a pile, a pair of similar axially aligned rotatable members, means for securing the members to a pile with the members mounted for rotation about an axis extending diametrically of the pile and perpendicular to the axis of the pile with the members spaced at substantially the same distance from the axis of the pile on opposite sides thereof, the center of gravity of each member being eccentric to the axis of rotation thereof, and means for rotating the members about their axis in unison in opposite directions with the centers of gravity of the pair of members in phase with each other.

8. Apparatus for actuating piles or the like which comprises, for use in combination with a pile, a plurality of pairs of similar axially aligned rotatable members, means for securing each pair of members to a pile with the members mounted symmetrically for rotation about an axis extending diametrically of the pile and perpendicular to the axis of the pile with the members of each pair spaced at substantially the same distance from the axis of the pile on opposite sides thereof, the center of gravity of each member being eccentric to the axis of rotation thereof, and means for rotating the members about their axis in unison in opposite directions with the centers of gravity of the pair of members in phase with each other.
